Primary Examiner — Sheryl Lane*Assistant Examiner* — Mark T. Philippss(74) *Attorney, Agent, or Firm* — Horst M. Kasper, Esq(57) **CLAIM**

The ornamental design for an actuator, as shown and described.

DESCRIPTION

FIG. 1 is a right side elevational view of an actuator showing my new design;

FIG. 2 is a front elevational view thereof;

FIG. 3 is a rear elevational view thereof;

FIG. 4 is a left side elevational view thereof;

FIG. 5 is a bottom plan view thereof;

FIG. 6 is a top plan view thereof;

FIG. 7 is a front, top perspective thereof;

FIG. 8 is a rear, bottom perspective thereof;

FIG. 9 is a cross sectional view taken at line 9-9 on FIG. 2; and,

FIG. 10 is a cross sectional view taken at line 10-10 on FIG. 2.

The broken line in the drawings shows environmental structures that form no part of the claimed design.
